BED RAIL ATTACHMENT

Robert L. Ray, Lenoir, N. C.

Application October 26, 1954, Serial No. 464,864

5 Claims. (Cl. 5—318)

This invention relates to a bed, and more particularly to an accessory for attachment to a bed for supporting various articles such as articles of clothing or the like.

The object of the invention is to provide an accessory for attachment to a rail of a bed whereby articles of clothing such as pants, coats, hats and the like can be conveniently supported adjacent to the bed.

Another object of the invention is to provide an accessory which can be readily attached to a rail of a conventional bed without altering the construction of the bed and whereby the accessory can be pivoted to an out of the way position when it is not being used and wherein the accessory can provide a support for uprights which may be used for supporting garments or clothing adjacent to the bed or else the device will support canopies, curtains or the like or an additional bed above the main bed.

A further object of the invention is to provide a bed rail attachment which is extremely simple and inexpensive to manufacture.

Other objects and advantages will be apparent during the course of the following description.

In the accompanying drawings, forming a part of this application, and in which like numerals are used to designate like parts throughout the same:

Figure 1 is a side elevational view of the bed rail attachment shown attached to a bed rail and with the bed rail in section, and showing a vertically disposed clothes supporting pole or upright mounted in the attachment.

Figure 2 is a rear elevational view of the attachment of the present invention, attached to a bed rail.

Figure 3 is a bottom plan view of the bed rail attachment.

Figure 4 is a front elevational view of the device.

Figure 5 is a sectional view taken on the line 5—5 of Figure 4.

Figure 6 is a side elevational view showing a pair of the attachments or accessories being used for supporting a canopy on a bed.

Figure 7 is a side elevational view illustrating a pair of the accessories for supporting an additional bed above the main bed.

Figure 8 is a fragmentary perspective view showing the construction of the top bed and pole for the assembly of Figure 7.

Referring in detail to the drawings, the numeral 10 designates a portion of a bed rail of a conventional bed, and the bed rail 10 may include a horizontal leg or portion and a vertical leg or portion 12, Figure 1. The present invention is directed to an attachment or accessory which is indicated generally by the numeral 13, and the attachment 13 is adapted to be attached to the bed rail 10 for supporting clothing, or any other article.

The attachment comprises a plate 14 which is arranged contiguous to the upper surface of the leg 11, and there is further provided a bracket 15 which includes a first portion 16 that is arranged on the opposite side of the leg 11 from the plate 14. A suitable securing element

2

such as a bolt and nut assembly 17 interconnects the plates 14 and first portion 16 together.

Extending from the first portion 16 is an inclined portion 18 which is arranged angularly with respect to the 5 portion 16, and the second portion 18 terminates in a vertically disposed third portion 19. An arcuate web 20 extends from the lower edge of the third portion 19, and the web 20 has extending upwardly therefrom a vertically disposed fourth portion 21. The fourth portion 21 has 10 an arcuate web 22 on its upper end, and a vertically disposed fifth portion 23 depends from the web 22, and the portions 21 and 23 are arranged in spaced parallel relation with respect to each other.

The lower edge of the fifth portion 23 is provided with 15 a curved lip 24, and a lug 25 is arranged contiguous to one side of the leg 12 of the rail 10. The upper end of the lug 25 is shaped to provide a downturned finger 26 for engagement with the lip 24.

The accessory of the present invention further includes 20 a base 27 which is arranged in spaced parallel relation with respect to the fourth portion 21 of the bracket 15. Connected to the base 27 and carried thereby is a body member 28 which includes an intermediate offset portion 29, and extending from each end of the offset portion 29 25 are inclined or outwardly divergent sections 30 which each terminate in a flat section 31. A straight section 32 extends from the flat section 31, and each of the sections 32 terminates in an apertured ear 33. A suitable securing element has a bolt and nut assembly 34 extended 30 through each apertured ear 33 and into engagement with the base 27 for connecting the body member 28 to the base 27. A bolt and nut assembly 35 provides a swivel pin, and the bolt 35 extends through the offset section 29, 35 through the base 27, through the fourth portion 21, and through the lug 25. Due to the provision of the swivel pin 35, the base 27 and body member 28 can be pivoted from the vertical position of Figure 1 to a horizontal position in alignment with the bed rail 10 when the device is not being used whereby there will be no protruding members.

Extending outwardly from the flat sections 31 of the body member 28 are ring members 36 which are connected to the flat section 31 by bolt and nut assemblies 37. These ring members 36 are adapted to receive therein 45 an upright or post 38 which may have hooks 39 thereon for receiving coat hangers, hats or the like. For helping to maintain the upright 38 in its proper position, an arm 40 depends from the lowermost ring member 36, and a pointed hook 41 is arranged on the lower end of the arm 50 for engaging the bottom of the upright 38.

A means is provided for retaining the base 27 and its associated parts in their vertical position until these parts are to be shifted to a horizontal position, and this means comprises clamps or crowns 42 which are arranged on each end of the bracket 15. Each crown 42 includes an arcuate portion 43 which has flat portions 44 and 45 on its ends, and a securing element such as a bolt and nut assembly 46 interconnects the flat portions 45 and 44 to the ends of the bracket 15. The flat portions 45 are adapted to frictionally engage the projecting ends of the base 27 so as to prevent accidental movement thereof.

Referring to Figure 6 of the drawings there is shown a slightly modified arrangement wherein a plurality of the attachments 13 may be used for supporting uprights 48, and a pair of the uprights 48 may provide a support for a horizontally disposed curtain rod 49. Drapes or canopies 50 may be supported by the curtain rod 49, and the canopies 50 can be used for enhancing the attractiveness of the bed 47 and the drapes or canopies 50 may also be used for insuring greater privacy for the occupant of the bed 47.

Referring to Figures 7 and 8 of the drawings there is

shown a still further modified arrangement wherein a pair of the accessories 13 may be mounted on each side of the bed 47. Uprights 51 may extend upwardly from each of the devices 13, and the uprights or posts 51 may have angle irons 52 secured thereto and the angle irons 52 may be additionally supported by braces 53, Figure 8. The angle irons 52 may form part of an upper or auxiliary bed 54 whereby a double deck bed can be provided which includes the main bed 10 and the upper bed 54.

From the foregoing it is apparent that there has been provided an accessory or attachment which can be connected to a rail 10 of a bed whereby various articles can be supported conveniently thereon. A bolt and nut assembly 55 may connect the fourth portion 21 of the bracket to the third portion 19, Figures 1 and 2. In use the plate 14 and bracket 15 may be connected to the bed 10, as shown in the drawings, and then the upright 38 can be extended through the ring members 36 with the pointed hook 41 engaging the lower end of the upright 38. Thus, articles of clothing or the like can be readily and conveniently suspended or supported on one or more of the hook members 39. When the device is not being used, the bolt and nut assembly 35 can be loosened and the base 27 and body member 28 can be pivoted in unison about the swivel pin 35 so that the parts move from the vertical position shown in the drawings to a horizontal position in alignment with the longitudinal axis of the bed rail 10 whereby there will be no interference with movement into and out of the bed. The flat portions 45 of the clamps 42 frictionally engage the ends of the base 27 so as to maintain the parts immobile in their vertical position. Instead of supporting articles of clothes on the uprights 38, posts 48 may be supported or projected through the rings 36 whereby a curtain rod 49 having drapes or curtains 50 thereon can be supported as shown in Figure 6. In Figure 7 a plurality of the accessories are shown and each is indicated by the numeral 13, and the accessories provide supports for posts 51 which may have the framework 52 of an upper bed 54 connected thereto.

With the accessory of the present invention connected to the bed rail, clothing, hats, and the like will be close by so that the user will save walking to pick up these articles, and as shown in Figures 7 and 8 an upper bed can be supported above the lower bed as for example when there is not much space in the home or other locality. Other articles that can be supported include food trays, curtains or shades whereby such curtains will give the user of the bed more privacy. The device can also be used in hospitals, rest homes and the like and the device will fold either to the right or the left about the swivel pin 35. Due to the provision of the body member 28 having the outwardly spaced flat sections 31, the upright 38 will be able to clear the curved portions 43 of the clamps 42 when the device is pivoted. Washers can be used wherever necessary on the various bolts.

I claim:

1. An accessory for attachment to an L-shaped rail of a bed, said rail including a vertically disposed and a horizontally disposed portion, a plate arranged contiguous to the upper surface of the horizontal portion of said rail, a bracket including a first portion arranged below said plate on the opposite side of the horizontal portion of said bed rail from said plate, a second portion arranged angularly with respect to said first portion, a vertically disposed third portion extending downwardly from said second portion, a first arcuate rib on the lower end of

said third portion, a vertically disposed fourth portion extending upwardly from said web and arranged in spaced parallel relation with respect to said third portion, a second arcuate web extending from the upper end of said fourth portion, a vertically disposed fifth portion depending from said last named web, a curved lip on the lower end of said fifth portion, a lug arranged contiguous to one side of the vertical portion of said rail, a base arranged in spaced parallel relation with respect to said fourth portion, a body member including an intermediate offset section arranged contiguous to said base, a swivel pin extending through said offset section, base, fourth portion and lug, outwardly projecting inclined sections extending outwardly from said offset section, flat sections extending from said inclined sections and arranged in spaced parallel relation with respect to said base, securing elements extending outwardly from said flat sections and having rings thereon, inclined straight sections extending from said flat sections and terminating in apertured ears, and securing elements connecting said ears to said base.

10 2. The structure as defined in claim 1, and further including clamps having flat portions connected to the upper and lower ends of said bracket, an arcuate section extending from the flat portion of each clamp, and a flat section extending from each of said arcuate sections for frictionally engaging said base.

15 3. The structure as defined in claim 1, wherein said rings have a vertically disposed upright extending therethrough, a vertically disposed arm dependents from said body member, and a pointed hook on said arm for engagement with the lower end of said upright.

20 4. The structure as defined in claim 1, wherein said body member is adapted to pivot about said swivel pin.

25 5. An accessory for attachment to an L-shaped rail of a bed, said rail including a vertically disposed and a horizontally disposed portion, a plate arranged contiguous to the upper surface of the horizontal portion of said rail, a bracket including a first portion arranged below said plate on the opposite side of the horizontal portion of said bed rail from said plate, a second portion arranged angularly with respect to said first portion, a third portion extending downwardly from said second portion, a first rib on said third portion, a fourth portion extending upwardly from said web, a second arcuate web extending from the upper end of said fourth portion, a fifth portion depending from said last named web, a lip on the lower end of said fifth portion, a lug arranged contiguous to one side of the vertical portion of said rail, a base arranged in spaced parallel relation with respect to said fourth portion, a body member including an intermediate offset section arranged contiguous to said base, a swivel pin extending through said offset section, base, fourth portion and lug, outwardly projecting inclined sections extending outwardly from said offset sections, flat sections extending from said inclined sections, securing elements extending outwardly from said flat sections and having rings thereon, inclined straight sections extending from said flat sections and terminating in apertured ears, and securing elements connecting said ears to said base.
